UNITED STATES PATENT OFFICE.

WILLIAM G. ROWELL, OF BRIDGEPORT, CONNECTICUT.

WATER-FAUCET.

No. 842,017.

Specification of Letters Patent.

Patented Jan. 22, 1907.

Application filed June 23, 1905. Serial No. 266,611.

To all whom it may concern:

Be it known that I, WILLIAM G. ROWELL, a citizen of the United States, residing at Bridgeport, in the county of Fairfield and State of Connecticut, have invented certain new and useful Improvements in Water-Faucets; and I do hereby declare the following to be a full, clear, and exact description of the invention, such as will enable others skilled in the art to which it appertains to make and use the same.

My invention relates to water-faucets; and it consists in certain details of construction and combination of parts hereinafter fully set forth, and specifically designated by the claim.

In the accompanying drawings, Figures 1 and 2 are sectional elevations of my improved faucet, respectively showing the valve in closed and open positions. Fig. 3 is a detail sectional elevation of the valve-stem and valve disconnected, and Fig. 4 a detail sectional elevation of the cap.

Similar characters of reference denote like parts in the several figures of the drawings.

1 is the body of the faucet, 2 the nozzle, and 3 the connecting-shank. The body and nozzle are cored so as to leave a chamber 4 in the body and a passage 5 through the nozzle, which chamber and passage are always in direct communication with each other. The shank is also cored so as to leave a passage 6, which has no communication with the chamber 4 or passage 5 except through the opening 7 in the horizontally-disposed floor 8 of the body 1. This body 1 is threaded interiorly at its upper end, and a cap 9, having a threaded plug 10 and an annular shoulder 11, is driven within this body until the shoulder 11 impinges against the top of said body.

A recess 12 extends from the bottom of the plug up into the body of the cap, and an opening 13 extends from the top of the cap into said recess. Both this opening 13 and recess 12 are circular in cross-section, the diameter of the recess being greater than the diameter of the opening, so that an annular shoulder 14 is formed at the upper end of said recess. Within the wall of this recess are cut four separate female threads *a b c d*, each of which completes the circuit of said wall from a point at the top of said wall to a point at the bottom thereof.

Through the opening 13 extends the valve-spindle 15, and 16 is a gland surrounding the spindle and driven on the top of the cap 9

and inclosing any suitable packing 17. This spindle carries four separate male threads *e f g h*, which engage the female threads *a b c d*, so that it will be clear that when the spindle 60 is turned slightly its lengthwise movement will be considerable. The bottom of the spindle has a socket 18 formed therein, into which the stem 19 of the valve 20 fits loosely.

The depth of the socket is greater than the length of the stem. Both socket and stem are circular in cross-section, and the socket is provided with a vent 21 at its inner end, so that the valve can always have free play when the spindle is elevated, as will be presently explained.

Stem 19 is formed at its base with an enlarged part tapered on its upper face, it being noted that when valve 20 is raised by the pressure of water and is rotated by the water 75 the tapered portion of the valve will be subjected to equal wear throughout its bearing-face with respect to the lowered edge of the valve-spindle.

Around the top of the opening 7 is formed 80 a valve-seat 22, so that it will be clear that when the valve 20 is driven against said seat the water will be shut off, and when the spindle is elevated the force of the water will raise the valve to allow the water to flow out 85 through the nozzle.

Surmounting the spindle is any suitable handle 23, and by giving this a quarter-turn in one direction the valve can be fully opened, while a quarter-turn in the reverse 90 direction will completely close the valve.

By providing four separate threads, as above set forth, I am enabled to obtain an end thrust of the spindle on a quarter-turn thereof as great as a similar thrust produced 95 by a full turn of the spindle with a continuous threaded connection. This is a great advantage in water-faucets of the compression type, since the leakage is reduced to a minimum and the operation is rendered exceedingly rapid.

The valve-stem fits loosely within the socket at the bottom of the stem, and since this socket has a vent at the top the elevation of the valve-stem and the consequent 105 sudden flow of the water with full force through the faucet coming in contact with the valve will cause the valve to be rotated, so that the seating surface of the valve will be constantly changed with respect to the valve-seat, thus preventing undue wear upon any portion of the seat or valve. Moreover,

this quick operation of the faucet by means of the four separate threads, as above set forth, prevents any "hammering," such as is occasioned by the force of the water in the 5 instance of compression-faucets that are opened and closed by the operation of a slow screw.

The upward movement of the valve is checked by the abutment of the upper ends 10 of the male threads on the valve-stem against the shoulder 14, while the valve-seat itself arrests the downward movement of the valve.

Having thus described my invention, what 15 I claim as new, and desire to secure by Letters Patent, is—

In a faucet, the combination of a body portion having an interiorly-threaded upper end, a threaded cap engaging said end and 20 provided with a shoulder seating directly on said end, said cap being formed adjacent its bottom with a recess and with a reduced opening extending from said recess through the top of said cap, the junction of said recess and opening forming a shoulder, a valve-seat, a valve-spindle, the wall of said recess of the cap being formed throughout its length with a number of threads each of which completes the circuit of the wall from a point at 25 the top of the wall to a point at the bottom thereof, said valve-spindle being formed with like threads of the same number corre-

sponding in pitch thereto, said valve-spindle having a portion thereof projecting beyond said threads and having a socket formed in 35 its bottom and a side vent at a point directly at the top of said socket, a valve-stem extending in said socket having free rotary and vertical movement therein, and of less length than said socket, an enlarged base on 40 said valve-stem having a tapered upper face, a removable valve rigidly secured to the under face of said base, and a handle for rotating said spindle, said cap-shoulder at the junction of the recess and opening restricting 45 said spindle in its upward movement to a quarter-turn, and said valve-seat likewise restricting said spindle in its downward course to a quarter-turn, said valve-stem being of greater length than the greatest movement of said valve-spindle resulting from a 50 quarter-turn thereof, said valve being raised by the pressure of water when said valve-spindle is raised and being rotated by the action of the water whereby said tapered face of the valve will be subjected to equal wear throughout its bearing-face with respect to the lower edge of said valve-spindle.

In testimony whereof I affix my signature in presence of two witnesses.

WILLIAM G. ROWELL.
